ILLUMINATING STAND

Harvey N. Bliss, 106 Preston St., Windsor, Conn., assignor to The Britton Corporation, Newington, Conn., a corporation of Connecticut

Filed Sept. 29, 1964, Ser. No. 31,937

Term of patent 14 years

(Cl. D80—9)

I claim:

The ornamental design for an illuminating stand, as shown.
